Att. 1.

UNITED STATES PATENT OFFICE

2,306,297

BOOSTER PUMP SCREEN

Russell R. Curtis, Dayton, Ohio, assignor to Curtis Pump Company, Dayton, Ohio, a corporation of Ohio

Application August 14, 1941, Serial No. 406,742

14 Claims. (Cl. 183—2.5)

The present invention relates to high altitude fuel systems for aircraft and more particularly to filtering means therein for straining fuel before it is delivered to an engine.

The filter assembly herein illustrated and described is preferably, although not necessarily, adapted for use with a booster pump of the type disclosed in my copending application entitled "Booster pump for aircraft fuel systems," Serial No. 352,064, filed August 10, 1940.

In the specification of my copending application it is proposed to employ a booster pump in such an arrangement with respect to the fuel tank that fully liquid fuel may be fed from a vented tank source considerably above the altitude in which there is a separation of air, other fixed gases, or vapors from the liquid fuel therein. By using a centrifugal booster pump having a flared throat, the fuel is subjected to a whirlpool action as it leaves the fuel tank, whereby the lighter gaseous bubbles are thrown upwardly and outwardly into the tank while fully liquefied fuel is delivered under pressure to the delivery line of the fuel system.

It is important that the fuel thus delivered be free of any foreign matter which might be injected into the fuel tank when the latter is filled. Preferably, the fuel should be strained as it leaves the fuel tank and enters the booster pump. However, any filter assembly provided must necessarily be so arranged as to satisfactorily strain all of the fuel entering the booster pump without interfering with the separation of the gaseous bubbles from the fuel and without restricting their path of flow outwardly and upwardly from the booster pump throat through the fuel in the fuel tank.

It is, therefore, an important object of this invention to provide means for filtering liquid fuel in a fuel system at a point which does not interfere with the delivery of the fuel to an engine.

Another object of the present invention is to provide a filter assembly at the outlet of a fuel tank which will strain the fuel flowing therethrough without restricting the upward and outward flow of gaseous bubbles separated from the liquid fuel in the tank outlet.

A still further object of the present invention is to provide a screen assembly for the outlet of a fuel tank which guides the flow of fully liquid fuel to the pump while deflecting the flow of gaseous bubbles away from the incoming liquid fuel.

A still further object of the present invention is to provide a screen assembly at the outlet of

a fuel tank positioned over the inlet to a centrifugal booster pump in which a deflector member in the screen assembly directs the flow of fully liquid fuel into the pump along an axial path of the assembly and deflects the flow of gaseous bubbles separated from the fuel along an outward path back through the screen.

Still another object of the present invention is to provide a screen assembly in combination with the flared throat of a centrifugal booster pump at the outlet of a fuel tank for deflecting gaseous bubbles rising from the throat back through the screen at relatively high velocities.

The novel features believed to be characteristic of the present invention are set forth with particularity in the appended claims. The invention itself, however, both as to its organization and manner of construction, together with further objects and advantages thereof, may best be understood by reference to the following description taken in connection with the accompanying drawing, in which:

Figure 1 is a broken view in vertical cross section, with parts in elevation, of a filter assembly in a fuel system constructed and arranged in accordance with the principles of the present invention;

Figure 2 is a fragmentary top plan view in elevation of the screen assembly as seen substantially in the plane indicated by the line II—II and looking in the direction of the arrows;

Figure 3 is a view similar to Figure 2, illustrating details of construction of the screen assembly in a transverse section as taken substantially along the plane indicated by the line III—III of Figure 1; and,

Figure 4 is an enlarged fragmentary view in vertical section of a modified form of filter construction as seen in a vertical plane taken through the screen and deflector and illustrating screen portions of different sized mesh connected by the deflector member.

The portion of the fuel system illustrated in Figure 1 generally comprises a fuel tank 10, a booster pump 11 preferably but not necessarily mounted on the bottom wall of the tank, and a screen assembly 12 mounted over the throat opening of the booster pump.

The fuel tank 10 has a vent member 13 provided in the top wall thereof and an outlet opening 14 in its bottom wall within which the booster pump 11 is mounted.

An annular member 14a has an enlarged portion 14b adjacent the inner periphery thereof inserted into the opening 14 and an annular

flange portion 14c connected to the bottom wall of the tank around the opening 14 by means of a plurality of rivets 14d or the like.

A throat member 15 is positioned within the annular member 14a and is mounted thereon in a manner to be later described. The inner periphery of the throat member 15 has a tapered surface 16 and an annular inlet surface 17.

An annular outer shoulder 18 on the throat member provides a seat for a pump casing 19 which is connected to the annular member 14a by means of studs 14e. An internal volute chamber 20 in the pump casing opens along the outer periphery into a discharge member 21 which in turn is connected to a fuel delivery line 22.

The pump impeller comprises a hub 23, a flange 24 and a series of curved vanes 25. The impeller is secured to a driving shaft 26 by a key (not shown) and a nut 27.

The outer periphery of the impeller, defined by the ends of the vanes 25, is positioned between the throat member and an annular flange portion 28 on the inside of the pump casing 19 in order that the fuel be delivered under pressure through the volute 20 into the delivery line 22. A casing portion 29 houses the driving shaft 26 and is connected to a source of motive power for driving the impeller, such as an electric motor (not shown).

As liquid fuel 30 in the tank flows through the throat, the revolving impeller vanes 25 create a whirlpool action in the fuel. The portions 25a of the vanes which underlie the throat member 15 effect a radial pumping of the liquid fuel to deliver it under pressure to the outlet 21 while the vane portions 25b which underlie the throat opening 17 effect an agitation of the gas-fuel mixture flowing into the throat to beat bubbles out of the liquid. The whirlpool action within the fuel is funnel-shaped and the agitated fuel is whirled in a corkscrew path upwardly and outwardly from the vanes. This constant beating of the fuel effects an increased generation of gas and vapor bubbles over that which normally results from decreased atmospheric pressure alone as the aircraft rises in altitude. The bubbles are carried outwardly and upwardly by the liquid stream flowing in a corkscrew path leaving only fully liquid fuel at the axes of the throat to be pumped by the vanes into the outlet. It is to be noted that the gas bubbles form along the vane portions 25b and travel outwardly and upwardly away from the rotational axes of the impeller.

When the aircraft is operated at low altitudes, the fuel 30 is in a substantially fully liquid state and the pump impeller merely delivers the fuel under pressure into the delivery line. However, as the altitude range of the aircraft is increased, a point is eventually reached in which there is a separation of air, other fixed gases, or vapors from the liquid fuel in the tank. This condition is aggravated as the altitude is increased. When the fuel in the tank starts breaking up, scattered bubbles 31 will appear in the pond of fuel throughout the tank. As the liquid fuel flows through the throat, the revolving impeller vanes 25 create a whirlpool action. The portions 25a of the vanes, which underlie the throat, effect a radial pumping of the liquid fuel to deliver it under pressure to the outlet 21 while the vane portions 25b, within the throat opening defined by the annular inlet 17, effect an agitation of the gas-fuel mixture flowing into

the throat to beat out the bubbles from the fuel and to generate more bubbles from fixed gases and vapors about to be released from the liquid because of the increased vapor pressure due to decreased air pressure on the fuel.

Inasmuch as fine and coarse foreign matter may be inserted in to the fuel tank as the latter is being filled, some arrangement is necessary for straining the fuel so that filtered fuel is delivered to the engine carburetor. A fine mesh screen is usually incorporated in the fuel delivery line from which it is easily removed and cleaned. This screen filters fine particles of foreign matter from the fuel. When a booster pump is provided as in the present instance, it is necessary to screen any rigid particles from the fuel before it enters the pump as such particles would damage the vanes on the rotating impeller. In providing such a screen, it is essential that it be so constructed as not to interfere with the separation of the gaseous bubbles from the liquid fuel, as herein previously described. Such a screen assembly will now be described.

The screen or filter assembly 12 comprises a generally cylindrical screen member 32. The screen is preferably formed of material which is inert when submerged in fuel such as gasoline. It is also preferred that the coarseness of the screen be 8 mesh, although this may be varied as desired.

A ring member 33 is connected to the throat member 15 by means of screws 34 or the like. The ring member 33 has an upwardly extending flange 35 at its inner periphery for connection to the marginal peripheral surface at one end of the screen. Connection therebetween is effected by any suitable means, such as solder or the like.

It is to be noted that the diameter of the screen portion 32 is substantially the same as the diameter at the widest end of the tapered throat surface 16. This relationship will be explained in greater detail hereinafter.

A screen insert member 36, of the same material and mesh as the screen member 32, is inserted into the upper end thereof and connected thereto by any suitable means, such as solder or the like. Obviously the screen assembly 12 can be formed of screen material in the form of a cup of one-piece construction.

As best shown in Figures 1 and 3, a baffle or deflecting member 37 is connected to the inner periphery of the screen portion 32 by any suitable means, such as solder. This deflecting member is positioned in spaced relation from the lower or open end of the screen and preferably closer thereto than to the closed end. The deflecting member 37 is formed preferably of thin sheet brass having a substantially cylindrical portion 38 for connection to the screen portion 32 and a deflecting portion 39 in angular relation to the cylindrical portion. The deflecting portion 39 is apertured as at 40 and in the preferred form of construction the diameter of this aperture is substantially the same as the cylindrical surface 17 of the throat member.

It is preferred that the deflecting portion 39 slope inwardly toward the longitudinal axis of the screen assembly at an angle of approximately 60° from the side walls thereof. It is to be understood, however, that this angularity may be varied over a wide range.

As the light gas bubbles 31 are concentrated adjacent the annular throat surface 17, the whirlpool action created in the fuel pond by the impeller blades 25 forces the gas bubbles out-

wardly as they rise above the throat. Consequently, it is desirable that the cylindrical portion 32 of the screen assembly be positioned as close to the throat as possible so that the gas bubbles 31 will be forced through the screen portion thereof to travel outwardly in the fuel in the fuel tank before rising upwardly toward the top thereof. This permits fully liquid fuel to be drawn through the top and side portions of the screen assembly above the deflector member 37 without drawing the gas bubbles 31 back into the screen. This flow path of fully liquid fuel is illustrated in Figure 1 by the solid-line arrows. The fuel is screened or filtered as it is drawn through the screen assembly 12 and the fully liquid fuel is drawn axially downward into the booster pump 11 where it is delivered to the delivery line 22. This delivery is, of course, only under pressure greater than atmospheric when the booster pump is in operation.

As the light gas bubbles 31 rise above the booster pump throat and the whirlpool action forces them outwardly from the screen assembly 12, they strike the deflector and are deflected through the lower portion of the screen portion 32. Consequently, the deflector is positioned to deflect the greatest number of the free bubbles as they rise in a curved path. It is obvious that the angularity of the deflector portion 39 may be varied from a position extending radially inward from the side walls of the screen assembly to a position nearly tangential to the curved path of the bubbles.

A screen of the type shown in Figure 1 will tend to block the flow of bubbles 31 entrained with the liquid fuel passing through the lower screen portion in the corkscrew path. Obviously, this blocking action depends on the fineness of the screen, the size of the bubbles and the velocity of flow of the fuel in the cork-screw path caused by the agitation of the fuel by the impeller.

An impeller of the type illustrated causes fine bubbles to form along the tapered agitating portions 25b of the vanes. These bubbles and fuel are induced to flow outwardly and upwardly from the rotational axes of the impeller by its agitating action. As the bubbles collect together and rise upwardly in the fuel they increase in size. It is therefore necessary to position the screen as closely as possible to the throat to permit the bubbles to escape therethrough before growing to a size where they would be blocked by the screen mesh.

While the greater number of bubbles are thrown outwardly beyond the screen and rise to the surface of the fuel pond, many are pulled back toward the top of the screen in the path of fuel flowing toward the impeller. However, since the bubbles, when they reach the top portion of the screen, have grown in size and the velocity of fuel flow is low because of the large screen area through which the fuel enters, they will be trapped on the screen from where they rise to the surface of the fuel pond and escape.

It will be apparent from the foregoing description that the screen portion below the deflector member 37 must be sufficiently coarse to permit gaseous bubbles to flow therethrough in the stream of liquid fuel flowing in the corkscrew path generated by the impeller. Furthermore, it is highly desirable that the screen portion above the deflector 37 be sufficiently fine as to trap on the outside thereof the greater number 75 of gaseous bubbles following the relatively slow

stream of liquid fuel flowing into the screen to be drawn through the impeller and ejected under pressure. The low velocity of fuel flow and the trapping of bubbles permits the use of a modified screen assembly as illustrated in Figure 4.

In this modified form of construction, a screen assembly similar to the assembly 12 is provided. The lower portion 50 is preferably of 8 mesh screen or coarser and is positioned above the throat 15 and connected thereto by a ring member 33 and screws 34 in the same manner as shown in Figure 1. The deflecting member 37 has the lower portion only of its cylindrical portion 38 connected to the inner periphery of the screen portion 50 by solder or other suitable means.

The upper portion 51 of the screen, instead of being formed of screen material of 8 mesh, is formed of a mesh material of sufficient fineness to screen fine foreign material from the liquid fuel flowing as indicated by the solid-line arrows of Figure 1.

Consequently, the deflector portion 39 aids in deflecting gaseous bubbles through a coarse screen therebelow while the substantially gas-free liquid fuel flows through a fine screen above the deflector into an axial path where it is drawn downwardly into the booster pump.

Such a screen assembly could replace the usual filtering screen in the delivery line or, if it does not replace the usual filtering screen, it will augment filtering of the fuel before it reaches the engine carburetor.

It will be apparent from the foregoing that I have provided a filtering assembly for a gas and liquid separating device for use in a fuel system for aircraft. Furthermore, the arrangement of this invention provides a filtering assembly which defines flow paths for fully liquefied fuel and for the separated gas bubbles which rise in the fuel in the tank.

While a particular embodiment only of this invention has been illustrated it will, of course, be understood that the invention should not be limited thereto, since many modifications may be made and, therefore, it is contemplated by the appended claims to cover all such modifications as fall within the true spirit and scope of the present invention.

I claim as my invention:

1. In a gas and liquid separating device including a throat receiving gas and liquid from a pond, and an impeller effecting circulation of liquid in the pond and separation of gas bubbles from the liquid, the improvement comprising a filter in said pond surrounding said throat to strain liquid flowing to the throat, and means in said filter spaced from the throat to deflect gas bubbles from the impeller through the filter.
2. In a gas and liquid separating device including a throat receiving gas and liquid from a pond, and an impeller effecting circulation of liquid in the pond and separation of gas bubbles from the liquid, the improvement comprising a filter in said pond surrounding said throat to strain liquid flowing to the throat, and a deflector in said filter spaced from the throat substantially defining separate paths for liquid into said throat and for gas bubbles away from said throat and through said filter.
3. In a gas and liquid separating device including a throat receiving gas and liquid from a pond, and an impeller effecting circulation of liquid in the pond and separation of gas bub-

bles from the liquid, the improvement comprising a meshed filter in said pond surrounding and extending upwardly away from said throat to strain liquid flowing to said throat, and an apertured deflector member extending angularly inward from the side walls of said filter, said deflector defining a downward path for liquid flow through the apertured portion thereof and a deflecting surface for diverting the gas bubbles away from said path.

4. In a gas and liquid separating device including a throat receiving gas and liquid from a pond, and an impeller effecting circulation of liquid in the pond and separation of gas bubbles from the liquid, the improvement comprising a meshed filter in said pond surrounding and extending upwardly away from said throat to strain liquid flowing to said throat, a frusto-conical sheet metal deflector member extending inwardly from the side walls of said filter at an angle of substantially 60° therefrom, said deflector defining therethrough a downward axial path for liquid into said throat while deflecting the gas bubbles rising from the impeller outwardly through the filter.

5. In a gas and liquid separating device including a tapered throat receiving gas and liquid from a pond, and an impeller effecting circulation of liquid in the pond and separation of gas bubbles from the liquid, the improvement comprising a cylindrical meshed filter having a meshed closure wall at one end thereof, said filter closely surrounding the widest end of said tapered throat to strain liquid flowing into the throat, a sheet metal deflector member extending angularly inward from the side walls of said filter and having an axial opening therethrough, said deflector opening defining a downward path for liquid into said throat and said angularly extending portion deflecting gas bubbles rising from the impeller in a path outwardly through said filter.

6. A filter assembly for fluids comprising a cup-shaped meshed member, and a sheet metal deflector member extending inwardly from the inner periphery of said cup-shaped member in spaced relation from the open end thereof.

7. A filter assembly for fluids comprising a cylindrical meshed member, a meshed closure member at one end of said cylindrical member, and an apertured sheet metal deflector member extending inwardly from the inner periphery of said cylindrical member in spaced relation from the other end thereof.

8. A filter assembly for fluids comprising a cylindrical meshed member, supporting means for said cylinder member at one end thereof, a meshed closure member at the other end thereof, and an axially apertured sheet metal deflector member extending inwardly and at an acute angle from the side walls of said cylindrical member adjacent the supported end thereof.

9. A filter assembly for fluids comprising a cylindrical meshed member, supporting means for said cylindrical member at one end thereof, a flanged meshed closure member in the other end of said cylindrical member, and a deflector member in said cylindrical member in spaced relation from the supported end thereof, said deflector member being closer to said supported end than to said other end of the cylindrical member, said deflector member having a cylindrical portion connected to the inner periphery of said cylindrical member and an axially aper-

tured deflector portion extending inwardly and at an angle of substantially 60° from the side walls of said cylindrical member.

10. In a pump assembly including a tank, and a centrifugal pump having a fluid inlet throat receiving fluid from the tank and arranged to create a whirlpool in the tank, the improvement which comprises an apertured deflector member mounted in the tank in the whirlpool path for guiding fluid to the throat while deflecting fluid rising from the throat beyond the thus guided fluid.

11. In a booster pump including an inlet throat receiving liquid material from a pond and an impeller assembly having a pumping vane portion and an agitating ram portion for beating bubbles of gas and vapor out of the liquid to travel upwardly in the pond along a path diverging from the axis of the throat, the improvement of a strainer in the pond spanning the throat and having a coarse mesh portion in the path of the bubbles and a finer mesh portion in the path of liquid flowing to the throat.

12. A filter assembly adapted for disposal over the inlet of a pump having agitating means for beating out bubbles of gas and vapor from liquid passing through the filter and pumping means for pressuring the bubble freed liquid, which comprises an annular meshed member adapted to be positioned adjacent the inlet of such a pump, and a cup shaped meshed member forming an extension of said annular member for extending away from the inlet of such a pump, the mesh of said annular member being of greater coarseness than the mesh of said cup shaped member whereby liquid flowing to the pump is adapted to be filtered through the cup-shaped member and whereby bubbles freed from the pump are adapted to pass through the annular member.

13. A filter assembly adapted for disposal over the inlet of a pump having agitating means for beating out bubbles of gas and vapor from liquids passing through the filter and pumping means for pressuring the bubble freed liquids which comprises an annular meshed member adapted to be positioned adjacent the inlet of such a pump, a cup shaped meshed member forming an extension of said annular member and adapted to extend away from the inlet of such a pump, the mesh of said annular member being of greater coarseness than the mesh of said cup-shaped member, and an apertured deflector member between the annular meshed member and the cup-shaped meshed member extending inwardly from the filter assembly at an angle to the annular member whereby said assembly is adapted to be submerged in liquid and bubbles liberated by such a pump are adapted to flow through the annular member and rise in the liquid while being prevented from re-entering the filter by the cup-shaped member.

14. In a pump device for beating out bubbles of gas and vapor from a liquid flowing thereto and for pressuring the bubble-free liquid, the improvement of a relatively shallow annular guide shield adapted to be mounted in the liquid in spaced relation from said pump device to define a localized inlet flow path to the device and to cooperate with the pump device to define therebetween a flow path for the gas and vapor bubbles in the liquid.
